COLLAPSIBLE CONTAINER

Russell M. Glantzer, Washington, Pa., assignor to
 Tri-State Engineering Co., Washington, Pa., a
 corporation of Maryland

Application September 3, 1943, Serial No. 501,085

3 Claims. (Cl. 220—7)

My invention relates to collapsible containers which are particularly suitable as shipping containers for small parcels, a number of which can be placed within the container for shipment after which the container may be folded or collapsed, for storing or for return to a factory or shipping point for reuse. The container may of course be used for various other purposes, such as clothes hamper, display bins, etc.

One object of my invention is to provide a collapsible container which is of light weight, and which will nevertheless have sufficient rigidity and strength to support and protect articles packed therein.

Another object of my invention is to provide a container of the character referred to which can easily be manipulated to fasten the parts thereof rigidly in position to receive and transport articles of various kinds and which may easily be folded or collapsed after opening thereof and removal of contents therefrom.

Some of the forms which my invention may take are shown in the accompanying drawings, wherein Figure 1 is a plan view of the container with the parts expanded and locked together; Fig. 2 is a side view thereof; Fig. 3 is a fragmentary view showing an end closure or lid in partly opened condition; Fig. 4 shows the container with various parts thereof folded on one another and partly collapsed; Fig. 5 is a plan view showing a modification of the fastening device of Fig. 1; Fig. 6 is a sectional view thereof, taken on the line VI—VI of Fig. 5; Fig. 7 is a view taken on the line VII—VII of Fig. 5; Fig. 8 is a plan view showing another manner in which the parts of the container may be held in expanded position and locked, and Fig. 9 is an enlarged sectional view of a portion of the structure of Fig. 8.

Referring first to Figs. 1 to 4, the container comprises four vertical panels 10 which can suitably be of welded wire mesh of perhaps 9-gauge or 10-gauge wires. The panels are connected together at the vertical corners of the container by helical wires 11 which may be placed in position by a screwing or turning action wherein the helical turns are caused to embrace the adjacent marginal wires of two panels, the upper end of each helical wire 11 being then given a few close turns around the upper marginal wire of one of the panels, as indicated at 12 (Figs. 1 and 8), to anchor the helical wire against accidental turning movement after the parts are assembled.

The ends of the container have closure members which also are of mesh form. For convenience of description these end closures will be referred to as top and bottom members, though it will be understood that whichever end of the container happens to be uppermost can be

termed the top. The closure members at the ends of the receptacle are in the form of narrow panels, the bottom panel members being indicated by the numerals 14 and 15 (Fig. 4) that are hingedly connected to opposite side panels by helical wires 16 (only partly shown in Fig. 4). The fastenings for holding these panels 14 and 15 in closed position are not shown on the drawings, but are identical with the fastenings for the top closure members 18 and 19 that are hereinafter described.

The top panels 18—19 are pivotally connected at their outer edges to the top wires of the adjacent side panels, by helical wires 20 and 21, respectively (only partly shown in Fig. 4). The cover panel member 18 is connected to a plate 22 by having bends 23 formed in certain of its wires and projecting outwardly through holes in the plate. A rod 24 is inserted between these bends 23 and the upper face of the plate to connect the members firmly together. The plate 22 has formed thereon or welded thereto a pair of knuckles 25.

The cover member 18 has secured thereto a plate 26, the connection being made by having bends 27 formed in the mesh panel 18 and extending through holes in the plate, the parts being fastened in assembled relation by a retaining rod or wire 28, as in the case of the plate 22 and the panel 19. The plate 26 has two pairs of knuckles 30 and 31 in which a shaft or locking bar 32 is slideable for locking movement. A combined handle and latching bar 33 is pivotally mounted on the shaft 32. The plate 26 is also provided with holes through which the knuckles 25 will project when the lid is closed. When the parts are in the position shown in Fig. 1, the cover panels 18 and 19 are held in closed position by the locking bar 32, the bar having fingers or projections 35 that extend into the knuckles 25 and having projections 36 and 37 that extend into loops or eyes 38 which are welded to the adjacent side panels as shown more clearly in Fig. 3.

At this time the bent end 39 of the lever 33 has snap engagement with one of the strands in the panel 18, to hold it in releasable folded-down position. Should the bar 33 become accidentally raised such distance that its bent end 39 becomes disengaged from the mesh panel 18, one of the bends 27, at 27a (Fig. 1), will serve as a stop to prevent it and the bar 32 from being accidentally slid such distance as to disengage the bar from the knuckles 25 and eyes 38, since the lever bar 33 cannot be slid past 27a until it is raised to approximately vertical position.

In order to open the container the handle 39 will be unlatched and pushed edgewise, to slide the shaft or locking bar 32 in its knuckles 30 and 31, and thus move its projections or fingers 35,

36 and 37 out of the knuckles 25 and the eyes 38. These cover members 18 and 19 may then be swung back on their hinges 20 and 21 to thereby open the receptacle. If it is desired to collapse the receptacle the closure members 14 and 15 at the opposite end thereof will be unfastened in a similar manner and folded back.

When the ends of the receptacle are closed and fastened as above described, the cover members, by reason of the stiffening plates 22 and 26 and the locking rod 32, together with the anchorage of the ends of the rod to the eyes 38, brace the receptacle rigidly in rectangular or expanded position, against stresses of handling or shipping and will effectively protect the contents thereof against damage.

In Figs. 5, 6 and 7 I show a somewhat different latching arrangement for the bar 33a that corresponds to the bar 33 of Fig. 1. In this instance the bar 33a is bent outwardly and backwardly at 51 for engagement with a keeper 52 that is slidably supported on wires 53 of the closure panel 18.

When closing the receptacle the keeper 52 will be slid as far to the left as possible, as viewed in Fig. 5, thereupon the lever 33 is depressed to bring its hook 51 below the keeper. This depression is possible because there will be some inherent spring or resiliency of the parts. The keeper then is slid to the right to move it past the hook and into position overlying the lever 33a whereupon the lever will be allowed to spring up and the keeper slid back into the hook 51, as shown in Figs. 5 and 6.

Referring now to Figs. 8 and 9, I show an arrangement wherein the side panels are connected together and to the top and bottom panels in the same manner as in the structure of Figs. 1 to 4. In this instance, however, the closure panels or members are fastened closed in a different manner, the bottom closure member being secured in closed position by a bar 41 that is shown only fragmentarily, and the top panels 42 and 43 are fastened closed by a bar 44 that extends transversely of the bar 41. Here, as in the other form, the closure members are fastened in like manner to one another and description of the top fastening will apply also to the lower fastening. The inner edges of the panel members 42 have portions of their wires deflected or bent downwardly as shown at 45 (Fig. 9) and the other panel has portions of its wires deflected upwardly as at 46, the bends 45 and 46 being offset relative to one another in directions longitudinally of the bar 44 so that the bends 45 can pass through the panel 43 and the bends 46 pass through the panel 42, whereupon the bar 44 can be inserted between the bends to hold the inner edges of these panels 42 and 43 firmly together. The ends of the bar 44 will be passed under the uppermost or marginal wires 48 and 49 of the side panels, for more effective fastening or locking of the members 42—43 in closed position.

I claim as my invention:

1. A collapsible container comprising side panels hingedly connected in unitary relation at the corners of the container, an end closure therefor comprising a pair of panel elements that are respectively hingedly connected at their outer edges to two oppositely disposed side panels, outwardly-projecting knuckles on one of the panel elements, adjacent to the inner edge thereof and positioned to extend through perforations in the other panel element, when those areas of the panel elements near their inner edges are

brought into overlapping relation upon closing of the said elements, a locking bar carried by the second named panel element and slidable longitudinally of its inner edge, fingers on the bar positioned to be slid into and out of the said knuckles, through sliding movements of the locking bar when the panel elements are overlapped, a handle extending laterally of the bar and pivotally connected thereto but held by stop elements thereon against movement longitudinally thereof, whereby the handle can be pushed sidewise to shift the bar longitudinally, when the handle is raised, and means for releasably holding the handle folded against the said end closure.

2. A collapsible container comprising side panels hingedly connected in unitary relation at the corners of the container, an end closure therefor comprising a pair of panel elements that are respectively hingedly connected at their outer edges to two oppositely disposed side panels, outwardly-projecting knuckles on one of the panel elements, adjacent to the inner edge thereof and positioned to extend through perforations in the other panel element, when those areas of the panel elements near their inner edges are brought into overlapping relation upon closing of the said elements, a locking bar carried by the second named panel element and slidable longitudinally of its inner edge, fingers on the bar positioned to be slid into and out of the said knuckles, through sliding movements of the locking bar when the panel elements are overlapped, a handle extending laterally of the bar and pivotally connected thereto but held by stop elements thereon against movement longitudinally thereof, whereby the handle can be pushed sidewise to shift the bar longitudinally, when the handle is raised, and means for releasably holding the handle folded against the said end closure.

3. A collapsible container comprising side panels hingedly connected in unitary relation at the corners of the container, an end closure therefor comprising a pair of panel elements that are respectively hingedly connected at their outer edges to two oppositely disposed side panels, outwardly-projecting knuckles on one of the panel elements, adjacent to the inner edge thereof and positioned to extend through perforations in the other panel element when those areas of the panel elements near their inner edges are brought into overlapping relation upon closing of the said elements, upstanding ears on the sides of the container which are adjacent to the ends of the panel elements, in position to extend through perforations in the panel elements when they are brought into overlapping relation at their inner edges, a locking bar carried by the second named panel element and slidable longitudinally thereof, fingers on the bar and extension on the ends thereof, positioned to be slid into and out of the knuckles and ears, respectively, through sliding movements of the locking bar when the panels are overlapped at their inner edges, a handle extending laterally of the bar and pivotally connected thereto but held by stop elements thereon against movement longitudinally thereof, whereby the handle can be pushed sidewise to shift the bar longitudinally, when the handle is raised, and means for releasably holding the handle folded against the said end.

RUSSELL M. GLANTZER.
